UNITED STATES PATENT OFFICE.

FRANCIS R. HOSTETLER, OF KOKOMO, INDIANA.

GOVERNOR MECHANISM FOR INTERNAL-COMBUSTION ENGINES.

Application filed October 14, 1922. Serial No. 594,666.

To all whom it may concern:

Be it known that I, FRANCIS R. HOSTETLER, a citizen of the United States, residing at Kokomo, in the county of Howard and State of Indiana, have invented certain new and useful Improvements in Governor Mechanism for Internal-Combustion Engines, of which the following is a specification.

This invention pertains to an improved and novel governing mechanism for internal combustion engines, and while it may be readily utilized in connection with various types of combustion engines it is especially adapted for use in connection with Fordson tractors.

The prime object of the invention is to provide simple, durable, economical and thoroughly efficient centrifugally operated means for operating the throttle valve of an internal combustion engine.

A further object of the invention is to so construct, locate and combine the novel operating parts of this governing device as to insure the proper and safe operation of the throttle with respect to the speed of the engine.

The foregoing and such other objects as may appear from the ensuing description are accomplished by the construction, arrangement, combination and location of the parts hereinafter more fully described; illustrated in the accompanying drawings, and particularly pointed out in the claims appended hereto, it being understood that slight changes in the precise form, proportions and minor details of construction may be readily resorted to without departing from the spirit or sacrificing any of the advantages of the invention.

In the accompanying drawings forming a part of this specification it will be seen that:

Figure 1 is a transverse vertical section through the governor casing showing the novel means embodying my invention.

Fig. 2 is a detail elevation partly in section and showing the governor casing broken away in part, and

Figure 3 is a detail showing a Fordson throttle block in section and the throttle operating connections and engine block in side elevation.

Similar numerals of reference are employed to designate like parts in the several views of the drawings.

In the embodiment of this invention as illustrated, the numeral 1 indicates the up-

per section of the governor casing and 2 the lower section thereof, and fitted within the central portion of said casing are a series of bronze bushings 3, 4 and 5 respectively, 60 forming bearings for a shaft 6 centrally supported within the casing, said shaft having fixedly secured to its lowermost end a steel bevel gear wheel 7, adapted to engage and mesh with a similar bevel gear wheel 8 fixedly secured to one end portion of a Fordson cam shaft 9, as clearly shown in Fig. 1.

Suitably secured to the upper end of section 1 of the casing is a standard Fordson commutator 10 to the inner face of which is fixedly secured the contacts 11. The upper threaded end of the shaft 6 projects vertically through the upper end of section 1, and is provided with a sleeve 12 having a lateral extension 13 to which extension is suitably supported a roller 14 adapted to engage the inner face of the contacts, as the shaft 6 is caused to rotate, said sleeve 12 being retained in its proper position by the securing nut 12'. Fixedly secured to the shaft 6 80 within the casing with its lower face resting in contact with the roller thrust bearing 15 is a bracket casting 16 to which casting is pivotally secured at 17, a plurality of weights or balls 18 adapted to normally rest 85 in contact with the recessed portion 19 formed around the lower end portion of said casting.

Slidably secured around the shaft 6 by a pin 20 which passes through said shaft and disposed above the casting 19, is a sleeve 21 provided with vertical slots 22 for the reception of the pin 20, said sleeve being formed at its lower end with an outwardly and downwardly extended member 23 provided 90 with a curved recess 24 in its lower face at its outer edge portion for the reception of the peripheral portion of the weights or balls 18. Resting upon the upper end portion of the sleeve 21 is the roller thrust bearing 25, and loosely seated in contact with said roller bearing is the block or collar 26, surrounding the shaft 6, and formed with a laterally extended pin 27, at each side for engagement with the forked end portion of each eccentric arm 28, the said eccentric arms being fixedly secured to a shaft 29, which passes through and is supported by section 1 of the casing as shown in Fig. 2.

Fixed secured to the outer side portion 110 of the casing at each side thereof is an upright stud or rod 30, and to the upper end

portion of each of said studs or rods is rigidly secured a suitable plate or bar 31 adapted to rest in contact with the upper surface of the commutator 10 for securely retaining the same in its proper position on the top of the casing.

Rigidly secured to the outer side of the casing at one end thereof is an upwardly extended flat plate spring 32, with its upper free end resting in contact with one of the side faces of the governor arm or throttle regulating lever 33, to the upper end of which is connected one end of a connecting rod 34, the other end of said rod being secured to one arm of a bell crank lever 35 secured to the engine block 34' and to the other arm of said lever is connected one end of a rod 36, the other end of the latter being secured to an arm 37 secured to the throttle-operating shaft 38, which latter is secured to the butterfly throttle valve 39 fitted in the mixing chamber 40, and whereby the amount of fuel admitted to the engine is regulated by the governing mechanism and the speed of the engine thereby regulated.

The lower face of the outwardly and downwardly extended member 23 formed integral with the sleeve 21 normally resting substantially in contact with the weights 18 on the outer edge thereof the movement of the weights upward or downward immediately imparts an upward and downward movement of said sleeve 21, which action of the sleeve imparts a similar up and down movement to the collar 26 and eccentric arms 28 thereby imparting the proper back and forth movement, to the throttle controlling lever 33, as will be readily understood.

It will be seen that a screw-threaded pin 41, which is pressed through an opening formed through the spring plate 32 is provided with a suitable thumb nut 42, whereby proper tension may be provided in order to regulate the desired resistance of the throttle controlling lever with relation to the action of the governor weights.

It will be perceived that the section 2 of the casing is provided with an opening 43 formed therethrough for the reception of suitable bolts for fixedly securing the governor mechanism to the engine block.

The operation of my novel governing mechanism may be briefly described as follows:

As the shaft 6 which carries the operating parts of the governor is caused to revolve, the weights 18 carried by the fixed bracket casting and resting substantially in contact with the lower face of the outwardly and downwardly extended member 23 are by centrifugal force thrown outwardly and upwardly thereby forcing the sleeve 21 to move upwardly on said shaft, thus rais-

ing the block or sleeve 26, which action raises the eccentric arm 28 and turns the shaft 29 which imparts a backward and forward movement to the throttle regulating lever 33, through the medium of the connections leading from said lever 33 to the throttle valve 39.

It will be understood that the roller thrust bearing 25 is adapted to carry the load of the working parts of the governor which is caused by the tension on the spring plate 32 which rests against the lever 33 and by tightening the tension on the spring causes the engine to run faster while releasing the tension on said spring permits the engine to run slower; thus when the engine falls below speed, the weights will fall, and with a spring tension acting against the weights, said weights will move downward, which action opens the throttle enough to revive the speed, to the speed required, since as the weights rise it causes the throttle to close, and as the weights drop the throttle is caused to open. Hence, it will be readily evident that my improved governor mechanism is readily adapted to regulate the speed, so that with the slightest variation in the load it will open or close the throttle.

Having thus described my invention, what I claim and desire to secure by Letters Patent is:

1. A device of the character described, comprising a casing, a rotatable shaft mounted in bearings within the casing, a slotted slidable sleeve mounted on said shaft and formed at its lower end portion with an outwardly and downwardly extended member having a curved recess formed in its lower face at its outer edge, a bracket casting fixedly secured to the shaft beneath said sleeve having an annular recess formed in its outer face, centrifugally operated weights pivoted to said casting, a vertically slidable collar disposed above said sleeve formed with a plurality of lateral extensions, a horizontal shaft passing through the casing, eccentric arms engaging said lateral extensions and fixedly secured to said horizontal shaft, and a throttle operating lever secured to one end of said horizontal shaft.

2. A device of the character described, comprising a casing, a rotatable shaft mounted in bearings within the casing, a casting fixedly secured to said shaft and formed with an annular recess in its outer face, centrifugally operated weights pivotally connected to said casting, a slidable sleeve disposed above said casting formed with an outwardly and downwardly extended member having a curved recess in its lower face at its outer edge for the reception of said weights, a loose slidable collar disposed above said sleeve formed with a plurality of lateral extensions at its top portion, a horizontal shaft mounted through

- said casing, a plurality of eccentric arms engaging said extensions and fixedly secured to said horizontal shaft, and a throttle operating lever secured to one end of the 5 horizontal shaft.
3. A device of the character described, comprising a casing, a rotatable shaft mounted in bearings within the casing, a slotted slidable sleeve mounted on said shaft 10 and formed with an outwardly and downwardly extended member having a curved recess formed in its lower face at its outer edge, a bracket casting disposed below said sleeve formed with an annular recess in its 15 outer face, centrifugally operated weights secured to said casting, a loose slidable collar disposed above said sleeve formed with a plurality of lateral extensions at its top portion, a horizontal shaft mounted through 20 the casing, eccentric arms fixedly secured to said horizontal shaft and engaging with said extensions, and a throttle operating lever secured to one end of the horizontal shaft.
- 25 4. A device of the character described, comprising a casing, a rotatable shaft mounted within the casing, a bracket casting fixedly secured to said shaft, centrifugally operated weights pivotally connected 30 to the casting, a slotted slidable sleeve mounted in the shaft positioned above said casting having an outwardly and downwardly extended member formed with a curved recess in its lower face at its outer edge for the reception of said weights, a 35 loose slidable collar formed with a plurality of lateral extensions, a horizontal shaft mounted through the casing, eccentric arms fixedly secured to the horizontal shaft and engaging said extensions, and a throttle operating lever secured to one end of the horizontal shaft. 40
5. A governor mechanism of the character described, comprising a casing, a rotatable shaft mounted within the casing, a bracket casting 45 fixedly secured to the shaft with its lower face in contact with a roller bearing, centrifugally operated weights pivoted to the casting, a slidable sleeve mounted on the shaft disposed above the casting and formed with an outwardly and downwardly extended member having a curved recess 50 formed in its lower face near its outer edge, a loose slidable sleeve disposed above said member with its lower face in contact with a thrust roller bearing and formed with a plurality of lateral extensions, a horizontal shaft mounted through the casing, eccentric arms engaging with said extensions and fixedly secured to the horizontal shaft, a throttle controlling lever secured to one end of the said horizontal shaft, and a tensioned 55 adjusting device fixedly secured to the outside of the casing with its free end resting in contact with said lever. 60

FRANCIS R. HOSTETLER.
